CLAIM

The ornamental design for a handle for table cutlery as shown and described.

DESCRIPTION

1. Handle for table cutlery

1.1 is a perspective view of an embodiment of the Handle for table cutlery showing my new design;

1.2 is a front elevational view thereof;

1.3 is a rear elevational view thereof;

1.4 is an enlarged left side elevational view thereof;

1.5 is an enlarged right side elevational view thereof;

1.6 is a top view thereof; and

1.7 is a bottom view thereof.

The broken lines appearing in the figure drawings depict portions of the handle for table cutlery that form no part of the claimed design.

1 Claim, 7 Drawing Sheets
